UNITED STATES PATENT OFFICE

146,484

DESIGN FOR A FLOWER HOLDER

Frank N. Moore, Chicago, Ill.

Application January 18, 1946, Serial No. 125,701

Term of patent 3½ years

(Cl. D35—3)

To all whom it may concern:

Be it known that I, Frank N. Moore, a citizen of the United States, residing at Chicago, in the county of Cook and State of Illinois, have invented a new, original, and ornamental Design for Flower Holder, of which the following is a specification, reference being had to the accompanying drawing, forming part thereof.

The figure is a perspective view of a flower holder embodying my new design.

I claim:

The ornamental design for a flower holder, as shown and described.

FRANK N. MOORE,
